SURFACE DRAIN

John H. Schmid, Westfield, N. J., assignor to J. A. Zurn
Mfg. Co., Erie, Pa., a corporation of Pennsylvania

Application February 10, 1954, Serial No. 409,388

8 Claims. (Cl. 210—166)

This invention relates generally to drains and more particularly to surface drains adapted to accommodate large amounts of water. This application is a continuation in part of my co-pending application, Serial No. 229,605, which issued as Patent No. 2,689,017 on September 14, 1954.

As pointed out in my co-pending application, drains made in accordance with the teaching of the prior art and with which I am familiar do not provide means for the breaking up of the air entrapped in the water flowing through the reservoir of the drain and the outlet leading therefrom. In these prior drains, there is an eddy formed in the center of the drain by the water passing therethrough. In other words, water flowing in large quantities into a drain pipe tends to move spirally in a vortex or whirlpool upon entering the drain. As a result, a considerable amount of air entrapped is carried with the water from the reservoir and into the outlet pipe leading therethrough. This entrapped air reduces the head and greatly impedes the flow of water to the drain outlet pipe. The entrapped air also tends to effectively reduce the capacity of the drain line with the result that water is backed up on the surface being drained and a flood condition often results. Prior drains also permit a sudden contraction of the water flowing into the pipe from the surface, causing a relatively high loss of pressure at the entrance which greatly impedes the flow of water to the drain outlet.

In my co-pending application, I disclose a means for eliminating vortexes in a drain. In this application, I disclose a means for inhibiting vortexes and reducing the effect thereof. In some applications of drains, it is not necessary to completely eliminate vortexes therefrom but a satisfactory flow through the reservoir and the drain can be accomplished by reducing the effect of the vortex. In order to accomplish this, I provide radially extending fins on the inside of the reservoir which prevent a swirling action in the inside of the reservoir. The liquid friction between the liquid held against swirling by the fins reacts on the liquid in the center of a reservoir to materially reduce and, in some cases, entirely eliminate vortexes. This is of extreme importance in accomplishing the maximum flow through a drain pipe.

It is, accordingly, an object of my invention to overcome the above and other defects in surface drains and it is more particularly an object of my invention to provide a surface drain which is simple in construction, economical in cost, economical to manufacture, and efficient in operation.

Another object of my invention is to provide a surface drain which will inhibit the formation of an eddy in the reservoir.

Another object of my invention is to provide a drain which will increase the head of water therein and minimize the impedance to the flow of water through the drain.

Another object of this invention is to provide a surface drain which inhibits the entrapment of air in the water.

2

A further object of the invention is to provide a drain having fins in the reservoir thereof to inhibit the formation of vortexes.

With the above and other objects in view, the present invention consists of the combination and arrangement of parts hereinafter more fully described, illustrated in the accompanying drawing and more particularly pointed out in the appended claims, it being understood that changes may be made in the form, size, proportions, and minor details of construction without departing from the spirit or sacrificing any of the advantages of the invention.

In the drawing:

Fig. 1 is a side view partly in cross section of a drain according to my invention;

Fig. 2 is a cross sectional view taken on line 2—2 of Fig. 1;

Fig. 3 is a side view partly in cross section of another embodiment of the invention;

Fig. 4 is a cross sectional view taken in line 4—4 of the embodiment of the invention shown in Fig. 3;

Fig. 5 is a side view partly in cross section of still another embodiment of the invention; and

Fig. 6 is a fragmentary plan view of Fig. 5.

Now with more specific reference to the drawing, I show an embodiment of my invention in Fig. 1 wherein a cup shaped reservoir 20 has an internally threaded outlet 21 in the bottom thereof for threadable engagement with the male threaded end of an outlet pipe 22 leading therefrom. The reservoir 20 has an outwardly directed marginal flange 23 on the upper end thereof and has inwardly directed ears 24 with threaded apertures 25 on the inner side thereof. The bottom of the flange 23 is tapered at 26 and is adapted to engage a roof or similar structural element for support thereby. A clamping ring 28 is secured to the reservoir 20 by screw bolts 29 which extend through apertures 30 in the clamping ring 28 and threadably engage the threaded apertures 25 in the ears 24. The clamping ring 28 has an offset portion 31 corresponding to an offset grooved portion 32 in the flange 23 between which is clamped a conventional roofing paper 33. The upper side of the clamping ring 28 is substantially merged with the upper surface of the paper 33 of the roof. An upwardly extending guard ring 35 extends upwardly from the clamping ring 28 to form a shield against gravel and other heavy particles.

A dome strainer 38 is mounted on top of the reservoir 20. The lower portion 39 of the dome strainer 38 flares outwardly and upwardly at 39a. Opposed radially extending slots 43 therein extend downwardly to substantially the same horizontal plane as that of the roofing paper 33, thereby providing a drainage of water from the roof under normal conditions. The outer portion of the lower mating section 39 of the strainer 38 is spaced from the upper side of the ring 35 a predetermined distance, thereby forming an annular opening 39c of predetermined width to provide a strainer for preventing debris from passing into the pockets between the ring 35 and the member 39a.

The upper section 40 of the strainer 38 has circumferentially spaced vertically extending slots 46 in the lower portion thereof which permit the maximum flow of water to the reservoir 20. The upper section 40 of the strainer 38 is flared upwardly and inwardly toward the vertical axis of the dome strainer 38 in a direction substantially at right angles to the lower section 39 of the strainer 38 to permit the maximum flow of fluid through the strainer 38. The top 47 of the upper section 40 of the strainer 38 has rounded and spaced radially extending slots 48 formed therein. The inner section 49 of a support ring 50 on the lower half 39 of the strainer 38 is rounded so as to prevent sudden contraction of

fluid through the dome strainer 38 and to decrease the entrance loss in pressure due to the sudden contraction of the water as in conventional drains.

The supporting ring 50 of the strainer 38 has a leg 51 extending radially outwardly therefrom which forms a slot and is engaged by the inwardly directed member 50a. The leg 51 underlies the member 50a to form a bayonet joint by means of which the dome strainer 38 may be detachably secured to the clamping ring 28. The slots 46 in the upper section 40 of the strainer 38 are at an elevation with relation to the reservatory 20 on the top of the roof to substantially increase the head of the fluid in the reservatory 20 to carry off heavy rainfall due to cloudbursts and the like and they are particularly useful where paper, leaves, and other material tend to clog the drain openings formed in the lower section 39 in the strainer 38 and the opening between the lower portion 39 of the strainer 38 and the top of the guard ring 35.

Integral with the bottom of the reservatory 20, I form baffles 60 having inwardly extending portions 61. The baffles 60 are integral with the reservatory 20 and merge therewith at 62. The bottom of the baffles 60 are integral with the bottom of the reservatory 20 at 63. The baffles 60 are disposed at spaced points around the inner periphery of the reservatory 20. The tops 64 of the baffles 60 terminate adjacent the top of the reservatory 20. Inwardly extending ears 24 are provided to receive the bolts in the apertures 25. It will be noted that the baffles 60 generally form fins around the inside of the reservatory 20.

The drain is designed to readily carry off the normal rainfall. Upon the occurrence of an abnormal rainfall or cloudburst, the slots 46 in the upper section 40 of the dome strainer 38 come into play. The water passes through the slots 46 and is broken up by the fins or baffles 60 and the spiral or rotational velocity of the water passing through the drain is thereby greatly impeded without impeding the downward velocity of the water axially of the drain outlet. After striking the baffles 60, the water is directed downward through the outlet to the pipe 22, thereby minimizing the entrance loss of pressure. The baffles 60 prevent eddying or vortexes. The comparatively deep reservatory 20 permits a comparatively high head of water to form therein and inasmuch as the water passing through the slots 46 in the strainer 38 must pass a substantial distance through the strainer 38 on the reservatory 20 to discharge outlet 21 of the drain, substantially all of the air is vented from the water in this manner. Furthermore, because of the great distance the water must travel through the reservatory 20 from the strainer 38 and the lower lineal velocity thereof because of contact with the cross webs or baffles 60, a maximum separation of water from air results. The water is prevented from forming a vortex so as to entrain air therewith. The water hits the baffle members 60 and moves directly downward to the drain opening 21. The water in the center which might form a vortex is restrained therefrom by the frictional drag thereon by the water held in directed flow toward the center by the baffles 60. The inhibiting action of the baffles 60 in the reservatory 20, therefore, prevents vortexes and aids in releasing the entrained air in the water, thereby substantially increasing the flow through my novel drain.

In the embodiment of my invention shown in Figs. 3 and 4, I show a novel type of drain comprising a reservatory 120 having an outwardly extending flange 123, the flange 123 being generally constructed as the flange 23 in Fig. 1. The strainer may be supported on a shoulder 131 of the flange 123 by means of the ring 28 in the same manner that the ring 28 in Fig. 1 supports the strainer. The inner periphery of the reservatory 120 has inwardly scalloped sides 160 which form scallops on the inside of the reservatory 120 reacting on the water similar to the action of the baffles 60 in Fig. 1. The scallops may be considered fins for all practical purposes. The bottom

part of the reservatory 120 at 121 is threaded to receive the male end of a drainage pipe as in Fig. 1. The upper edge of the fins terminate in a shoulder 130 having a threaded hole 125 therein. The main distinction between this embodiment of my invention and that shown in Figs. 1 and 2 is the manner in which I form the scallops or baffles on the edges of the reservatory. These scallops eliminate the necessity of casting baffles integral with the inside of the reservatory and result in a simplification in the manufacturing process of the reservatory.

In Fig. 5, I show a reservatory 220 similar to the reservatory 20 in Fig. 1; however, the reservatory in this embodiment of the invention is adapted for use as a surface drain and has an upwardly extending flange 240 having a stepped portion 241 which provides a ledge 242 to support the strainer 243. Baffles 260 are cast inside the inner periphery of the reservatory 220 and are integral therewith and join the reservatory 220 at 262. The outwardly extending flange 226 is provided for support on a floor or the like. Drain holes 270 allow water to flow into the reservatory 220 which may flow down onto the flange 226 on the top of flange 240.

In the foregoing specification, I have set forth the invention in its preferred practical forms but I am aware that the structure shown is capable of modification within a range of equivalents without departing from the invention which is to be understood is broadly novel as is commensurate with the appended claims.

The embodiments of the invention in which an exclusive property or privilege is claimed are defined as follows:

1. A surface drain for handling large quantities of water comprising an open cup shaped reservatory, said reservatory having a generally flat bottom, a discharge outlet in said bottom, side walls extending upwardly from said bottom, said discharge outlet being substantially smaller in transverse cross sectional area than the transverse cross sectional area of said reservatory, and spaced, radially extending baffles attached to the inside of said reservatory, said baffles being spaced along the inner periphery of said reservatory and extending parallel to the axis of said reservatory, said baffles terminating adjacent the outside edge of said outlet and extending upwardly and terminating near the top of said reservatory.

2. The surface drain recited in claim 1 wherein bosses are formed integral with the top of said baffles, said bosses being bored to receive means to hold a strainer in rigid relation with said reservatory.

3. The surface drain recited in claim 1 wherein a peripheral flange extends outward from the intermediate portion of said reservatory and a portion of said reservatory extends upward from said flange and holes are formed in the sides of said reservatory adjacent said flange.

4. A surface drain for handling large quantities of water comprising an open cup shaped reservatory, said reservatory having a discharge outlet in the bottom thereof, said discharge outlet being substantially smaller in transverse cross sectional area than the transverse cross sectional area of said reservatory, and spaced radially extending baffles attached to the inside of the walls of said reservatory, said baffles terminating adjacent the outside edge of said outlet and extending upwardly and terminating near the top of said reservatory, the inner periphery of said reservatory being formed in the shape of scallops, thereby forming said baffles.

5. The surface drain recited in claim 4 wherein threaded bosses are provided in the top portion of said scallops and a strainer is supported on said scallops and on said bosses.

6. The surface drain recited in claim 4 wherein the upper edge portion of said reservatory has a stepped portion forming a ledge, one edge of said baffles terminating at said stepped portion forming a continuation therewith, and a strainer means supported on said ledge and on said baffles.

7. A surface drain for handling large quantities of water comprising a cup shaped reservoiry body having an inlet opening formed therein, said reservoiry body having a discharge outlet formed therein and spaced from said inlet opening, and spaced radially and axially extending baffles attached to the inside surface of said reservoiry body to prevent turbulence in water in said reservoiry body, said baffles comprising inwardly extending scallops formed by the sides of said reservoiry body bent inwardly at spaced points around the periphery thereof. 10

8. The surface drain recited in claim 7 wherein the upper edge of said scallops terminates in a shoulder and a strainer is supported on said shoulder.
